DESIGN FOR A COMBINATION CORSAGE HANDKERCHIEF AND PERFUME CON- TAINER

Charles J. Romer, New York, N. Y.

Application September 25, 1936, Serial No. 65,008

Term of patent 3½ years

To all whom it may concern:

Be it known that I, Charles J. Romer, a citizen of the United States of America, residing in Manhattan, county of New York and State of New York, have invented a new, original, and ornamental Design for a Combination Corsage Handkerchief and Perfume Container, of which the following is a specification, reference being had to the accompanying drawing, forming part thereof, wherein, tainer, showing the handkerchief member thereof in a hanging position, and disclosing the upper portion of the perfume container.

The design is characterized by the arrangement and/or association as shown of a handkerchief with a perfume container and the particular ornamentation appearing on the handkerchief.

The sides of the article in the two views are like the face views shown.

I claim:

The ornamental design for a combination corsage handkerchief and perfume container, substantially as shown, and described.

CHARLES J. ROMER.
